POWER CABLE CONDUCTOR FOR REDUCING WINDAGE

Joseph R. McLoughlin, Burnt Hills, N.Y., assignor to General Electric Company, a corporation of New York Filed Dec. 24, 1964, Ser. No. 420,977

7 Claims. (Cl. 174—42)

This invention relates to electrical conductors, and more specifically, to electrical conductors constructed in a manner to reduce windage losses, corona losses, and radio frequency interference thereon.

In the transmission of high voltages over electrical power cables, some of the most frequently occurring difficulties are the effects of windage forces and corona losses on the transmission cable, and the propagation of radio frequency interference by the cable. These difficulties have led to numerous attempts at overcoming them individually, mostly with expensive and often unwieldy equipment. Vibration effects caused by windage have been somewhat lessened by the hanging of weights at appropriate places along the conductor. Attempts have been made to overcome corona losses by encasing the transmission cable in a surrounding sheath filled with graphite or other suitable material. Corona losses are reduced to some extent by this method but windage difficulties are greatly increased, since one of the worst shapes for windage purposes is the circular cable shape, and now this circular shape has been increased in diameter and therefore the windage difficulties are accordingly increased. There has been very little work along the line of shaping the conductor itself so that windage, corona losses and radio frequency interference are overcome at the same time when the cable is originally installed. The need then arises for an electrical conductor for a transmission cable that is constructed to overcome windage losses, corona losses and radio frequency interference thereon.

In my copending application entitled "Covering for Power Line Conductors To Reduce Windage, Corona Loss and Radio Frequency Interference," Serial No. 421,017, I have disclosed apparatus that is added to a circular power conductor or other structure for overcoming windage, corona losses and radio frequency interference thereon. In the present application, I cover the use of a conductor that is designed in itself to overcome windage effects, radio frequency interference and corona losses thereon.

My invention envisions an electrical conductor having an overall aerodynamic air foil shape that induces streamlined flow around its surface for reducing windage losses and also having a conducting surface for reducing radio frequency interference and corona losses thereon.

The chief object of my invention is the provision of an electrical conductor having an overall air foil shape to promote even streamlined flow over its surface to reduce windage losses thereon.

Another object of my invention is the provision of an electrical conductor which has an air foil shape to reduce windage losses and which has conducting means for reducing corona losses thereon.

Another object of my invention is the provision of an electrical conductor having an aerodynamic air foil shape to reduce windage losses and having a coating of a semiconductor to provide means for overcoming corona losses and radio frequency interference thereon.

Another object of my invention is the provision of an electrical conductor having an air foil shape for overcoming windage losses and having a conducting surface that increases the effective circumference of the conductor to substantially reduce corona losses and radio frequency interference thereon.

A further object of my invention is the provision of an

2

electrical conductor shaped to maximize torsional rigidity that is combined with a foam material to form an overall streamlined shape to promote even nonturbulent flow around its surface for reducing windage and corona losses thereon

These and other objects of my invention will be more readily perceived from the description which follows.

One of the features of my invention is a highly efficient electrical transmission cable having a flat aerodynamic air foil shape that promotes streamlined non-turbulent flow over its surface to substantially reduce windage losses, and which surface is also a conductor or semiconductor to increase the effective circumference of the cable to overcome corona losses and radio frequency interference thereon.

The attached drawing illustrates preferred embodiments of my invention in which:

FIGURE 1 is a cross-sectional view of the conductor of my invention;

FIGURE 2 is a cross-sectional view of a modification of the conductor of FIGURE 1;

FIGURE 3 is a cross-sectional view of a further modification of the conductor of FIGURE 1; and

FIGURE 4 is a cross-sectional view of a modification of the conductor of FIGURE 3.

In FIGURE 1 there is shown a cross-sectional view of an air foil shaped conductor embodying my invention. The construction includes electrical conductor 2 which is constructed of copper, aluminum or any other material generally used for the conduction of electrical current. Conductor 2 has an air foil shape having a cross-sectional length which is horizontal and much greater than its cross-sectional width. This shape generally comprises two rounded ends 4 interconnected by suitable means to form this overall streamlined shape. In FIGURE 1 such means comprise center member 5 which provides electrical conductivity and structural and torsional rigidity between ends 4. Member 5 may be integral with ends 4 or alternatively separately secured thereto. The cross-sectional current carrying area of conductor 2 is then quite large since ends 4 and center members 5 all carry current and, therefore, high currents can be effectively carried by the conductor. Light weight material 6 is placed on either side of center bar 5 to fill areas 8 between the ends 4 of the conductor and center bar 5, to form a smooth surface so that air flows in a streamline manner around conductor 2. This smooth outer surface is shown as being straight but it might also be slightly convex outward. Light weight material 6 may comprise a foam material such as polystyrene, polyethylene, polypropylene, epoxy, rubber, urethane, polyvinyl chloride foams, or any suitable foamy material that is light in weight relative to the cable and easy installed. Connecting end tips 7 of conductor ends 4 there is a thin layer 10 of a semiconducting material or conducting material, comprising either a coating on the outer surface of foam 6, or a thin jacket over it, to aid in effectively reducing corona loss and radio frequency propagation on conductor 2, as will subsequently be discussed.

In operation, the cable is installed in a horizontal position with center bar 5, which is coincidental with the cross-sectional axis of symmetry of the conductor, parallel to the earth. Since wind generally blows in a horizontal plane, or at slight angles thereto, the force of the wind impinges on either end 4 of the electrical conductor. Ends 4 are rounded in an aerodynamic manner approximating an air foil shape so that air currents flow evenly in a streamline manner over surfaces 9 and either end 4 to minimize turbulent vertical flow around and behind conductor 2 and thereby substantially reduce the windage drag force thereon. It is important to note that for effective operation of an air foil, the streamlined shape

must be the last surface the air flows over. Therefore, regardless of the direction of the wind, both ends 4 are shaped in the same aerodynamic manner so that the air flow over the conductor always terminates its flow in a streamlined manner over either end 4. Conductor 2 because of its elongated cross-section, has low windage losses, whereas an equivalent circular conductor would have substantially greater losses due to turbulence and pressure gradients around its circumference. Thus, conductor 2 is substantially larger than a circular conductor having an equivalent cross-sectional conducting area, but nevertheless conductor 2 has far less windage drag effect thereon (probably on the order of 20 percent of the windage of a circular conductor of the same cross-sectional conducting area) because of its streamlined construction.

By the employment of a thin layer of semiconducting or conducting material 10 on the outside of foam material 6, the effective circumference of conductor 2 for corona reduction purposes becomes the outer circumference including this coating layer 10 and ends 4 of the conductor. This effective conductor circumference is then far greater than it would be for a circular conductor of the same cross-sectional conducting area. Corona losses and the subsequent luminescent ionization of the air surrounding the conductor, which are inversely proportional to the effective perimeter of the conductor are thus reduced substantially, by this increase in perimeter of the conductor. The effective circumference of the conductor is then increased in a manner that avoids sharp bends and small radii, which are points of excessive corona discharge. When thin skin 10 is made semiconductive, with the proper resistivity, radio frequency interference is substantially reduced by the attenuation of radio frequency waves along the conductor. This radio frequency interference reduction only takes place with a semiconducting coating but the corona loss reduction function takes place effectively with either a semiconducting or a conducting coating.

It is also noted that the swing angle of the cable with this conductor shape is also substantially reduced by virtue of negative lift or pressure downward as the conductor swings out to thereby reduce the angle to which it swings. It is also noted that a negative angle of attack with respect to the wind direction also decreases this swing angle.

In FIGURE 2 there is shown a modification of the device of FIGURE 1 whereby end sections 20 of conductor 19 are semicircular in cross-sectional area, thereby providing for a greater conducting area within the same total cross-sectional area as FIGURE 1. Because of these ends 20, the polar moment of inertia of the conductor is substantially increased with only a small increase in weight thereof. Such an increase in the polar moment of inertia helps to prevent twisting of the conductor caused by the asymmetry of wind forces on the conductor. As with FIGURE 1, FIGURE 2 has filler 22 of a light weight material and skin 24 of a semiconductor or conductor. The operation of FIGURE 2 is the same as that of FIGURE 1 in reducing windage, corona loss and radio frequency interference thereon.

In FIGURE 3 there is shown a hollow conductor 30 having the same air foil cross-sectional shape as that of the overall member of the mode of FIGURE 1 or 2. Conductor 30 is made of a typical conducting material such as copper or aluminum and has an air foil shape which includes flat or slightly curved bottom and top surfaces 32 and 33 and rounded ends 34 which together form one integral unitary structure. By making the conductor hollow, the outer perimeter is increased, over a circular conductor, while the cross-sectional conducting area and weight are kept constant. This, of course, results in an effective outside circumference that is substantially larger than a circular conductor of the same cross-sectional area and as previously mentioned, the greater the effective circumference of the conductor, the

less the corona loss. A simple method is then provided for reducing corona losses while providing low windage effects and high resistance to torsion.

It will be appreciated that the overall shape of conductor 30 is a streamlined one since it has the same shape as the overall member of FIGURE 1 or 2. Ends 34 which come into contact with the wind as it is leaving conductor 30 are aerodynamically curved as is all of member 30 to facilitate even streamline flow of air currents around and behind its surface. Turbulence that would be inherent in a circular conductor whether the circular conductor were hollow or solid is thus avoided. Swing angles are also substantially reduced because of the reduction of windage losses. It is also noted that transportation of conductor 30 is relatively easy because of a high degree of flexibility not inherent in hollow circular conductors.

In FIGURE 4 there is illustrated a conductor having U cup shaped ends 40 which fit snugly over end braces 42. In rolling long metal forms it is often easy to employ a rod on each side as a support, therefore, rod 42 and its counterpart on the other side (not illustrated) form a brace on each end of conductor 41 as it is being formed. Braces 42 also provide added torsional stiffness to the entire conductor when it is employed in a high windage field. The thin coating 43 and the rounded ends 44 are employed in the same manner as the mode of FIGURES 1 and 2 for reduction of windage, corona losses and radio frequency interference thereon.

It is noted that, with the modes of the conductor 1 have illustrated and described, thermal transfer by convection or radiation, is easily accomplished because of the large areas of the conducting surface that are exposed to the atmosphere. In FIGURE 1, ends 4, FIGURE 2, ends 20, and in FIGURE 4, ends 44, have their outer surfaces completely exposed to the atmosphere and in FIGURE 3 the entire outer surface of the conductor is exposed to the atmosphere. There will be no difficulty with heating on the hollow conductor of FIGURE 3 since the conductor itself is a good thermal conductor and therefore dissipates the heat through the conductor walls to the outside ambient air.

It is also noted that, with the various modes of my invention because of the large polar moments of inertia, a high degree of torsional stiffness of the conductors to prevent twisting is achieved.

Typical coatings that are used for the outside skin 10 in FIGURE 1, 24 in FIGURE 2, or 43 in FIGURE 4 are phenolic resin, polyethylene, polyurethane, polyvinyl chloride, rubber or other polymers, which may bear carbon black or metal particles to provide a semiconducting surface. This skin may either be a coating or a separate thin sleeve that is secured to the main member.

It is now apparent that my invention attains the objectives set forth. Apparatus embodying the invention is sturdy in construction and well adapted for use in conjunction with various environments. Windage, corona loss and radio frequency interference are substantially reduced on power cables while maintaining torsional rigidity thereon.

Specific embodiments of my invention have been illustrated but the invention is not limited thereto since many modifications may be made by one skilled in the art and the appended claims are intended to cover all such modifications as fall within the true spirit and scope of my invention.

What I claim as new and desire to secure by Letters Patent of the United States is:

1. An apparatus for reducing the effects of windage, corona loss and radio frequency interference on electrical transmission lines comprising an air foil shaped conductor having a cross-sectional length greater than its cross-sectional height, a trailing edge at one end of said cross-sectional

length of said conductor positioned on the opposite side of the conductor from where the wind is coming and with the cross-sectional length of said conductor being in a plane parallel to the direction of the wind for the wind to pass smoothly around the conductor in a streamlined manner to reduce the effects of windage thereon, and

means for providing a large conducting circumference on said conductor for reducing corona loss and radio frequency interference thereon.

2. An apparatus for reducing the effects of windage and corona loss on electrical transmission lines comprising an air foil shaped conductor having a cross-sectional length greater than its cross-sectional height,

trailing edges on said conductor at both ends of said cross-sectional length so that one of said trailing edges is always positioned on the opposite side of the conductor from where the wind is coming, and with the cross-sectional length of said conductor being in a plane parallel to the direction of the wind for the wind to pass smoothly around the conductor in a streamlined manner to reduce the effects of windage thereon,

a central member interconnecting said trailing edges to provide torsional rigidity to said conductor,

conducting means interconnecting said edges for providing a large, smooth conducting circumference for reducing corona loss on the conductor.

3. An apparatus for reducing the effects of windage, corona loss and radio frequency interference on electrical transmission lines comprising

an air foil shaped conductor having a cross-sectional length greater than its cross-sectional height,

trailing edges on said conductor at both ends of said cross-sectional length, so that one of said trailing edges is always positioned on the opposite side of the conductor from where the wind is coming, and with the cross-sectional length of said conductor being in a plane parallel to the direction of the wind, for the wind to pass smoothly around the conductor in a streamlined manner to reduce the effects of windage thereon,

a central member interconnecting said trailing edges to provide torsional rigidity to said conductor,

semi-conducting means interconnecting said edges for providing a large, smooth conducting circumference for reducing corona loss and radio frequency interference on the conductor,

filler means between said central member and said semi-conducting means to provide support thereto.

4. An apparatus for reducing the effects of windage,

corona loss and radio frequency interference on electrical transmission lines as defined in claim 3 where said edges are semi-circular in cross-sectional area.

5. An apparatus for reducing the effects of windage, corona loss and radio frequency interference on electrical transmission lines comprising

an air foil shaped conductor having a cross-sectional length greater than its cross-sectional height,

U-shaped trailing edges on said conductor at both ends of said cross-sectional length, so that one of said trailing edges is always positioned on the opposite side of the conductor from where the wind is coming, and with the cross-sectional length of said conductor being in a plane parallel to the direction of the wind, for the wind to pass smoothly around the conductor in a streamlined manner to reduce the effects of windage thereon, a central member interconnecting said trailing edges to provide torsional rigidity to said conductor,

semi-conducting means interconnecting said edges for providing a large smooth conducting circumference for reducing corona loss and radio frequency interference on the conductor,

filler means between said central member and said semi-conducting means to provide support thereto,

rods placed within the U-shaped edges of the conductor to aid in providing torsional rigidity thereto.

6. An apparatus for reducing the effects of windage, corona loss and radio frequency interference on electrical transmission lines as set forth in claim 3 in which said edges are a semicircular segment in cross section area to prevent twist.

7. An apparatus for reducing the effects of windage, corona loss and radio frequency interference on electrical transmission lines as set forth in claim 5 in which said central member is attached to said U-shaped trailing edges at the bottom of the U and the stiffening rods are fastened into the open end of the U to provide a smooth exterior surface and prevent twist.
